UNITED STATES PATENT OFFICE

CHARLES A. MEALY, OF WEST BARRINGTON, RHODE ISLAND, ASSIGNOR TO THE ⁶¹
HADLEY COMPANY, INC., OF PROVIDENCE, RHODE ISLAND, A CORPORATION OF
RHODE ISLAND

BRACELET CONSTRUCTION

Application filed December 10, 1930. Serial No. 501,266.

This invention relates to improvements in bracelets for wrist watches or the like, and the principal purpose of the invention is to provide a flexible bracelet band, belt, strap, or the like, which is unique in construction and design, comfortable to the wearer, and distinctly ornamental and attractive in appearance.

More specifically, the general object of the invention is the provision of a flexible bracelet band having a body portion provided with series of spaced openings fitted with metal reinforcements of pleasing design, and strengthening links engaging the reinforcing elements of adjacent openings so that longitudinal strain upon the bracelet is borne largely by the metal reinforcements and links rather than by the body material itself.

Recommended embodiments of the invention are illustrated in the accompanying drawings, in which:

Fig. 1 is a plan view of a section of a watch bracelet embodying the aforesaid improvements;

Fig. 2 is a central longitudinal section of the bracelet member;

Fig. 3 is a plan view of a modified form of bracelet;

Fig. 4 is a similar view illustrating a further modification;

Fig. 5 is a section taken on line 5—5 of Fig. 4;

Fig. 6 is a perspective view of one of the strengthening links shown in Figs. 1, 2 and 3; and

Fig. 7 is a sectional view through an optional form of reinforcement.

The body portion 8 of the improved bracelet may be formed of leather, fabric, or other ornamental material suitable for bracelets, belts or the like, and said body has a series of spaced apertures 9 which lighten the strap and enhance the appearance of the bracelet in accordance with the present vogue which tends to endorse open-link chains or bracelets for personal wear. The openings 9 are fitted with eyelets 10 or other metal reinforcements of attractive finish and pleasing design which preferably

afford a desirable contrast to the body of the strap or band 8.

The eyelets 10 may consist of a single piece of metal inserted through the apertures and having peripheral flanges 11 ⁵⁵ curled or crimped over upon opposite faces of the strap (Fig. 2); or they may comprise a pair of separable, telescoping members 12, 13, as shown in Fig. 7. It will be understood that the eyelets may be rectangular, ⁶⁰ circular or of any appropriate contour and that their exposed surfaces may be smooth finished or ornamented, as desired.

The connecting members 14 which straddle the adjacent sides of adjoining eyelets ⁶⁵ and which strengthen the eyeleted portions of the strap 8 against longitudinal strain, preferably comprise closed metal links which pass through adjacent openings 9 and are permanently or removably secured in ⁷⁰ engagement with the eyelets 10. As best shown in Fig. 6, each link may be formed from a hollow blank of ductile metal rolled into tubular shape so that its ends 15 are in abutting relation, thus providing spaced, ⁷⁵ parallel crossbars 14 which encircle an adjacent pair of eyelets 10. The ends 15 preferably meet at the under side of the band 8, so that the connecting members appear to comprise individual twin links when observed from the upper or outer side of the bracelet.

In the modification shown in Fig. 3, the eyeleted portions 18 of the strap body are separated in the manner of spaced rings or ⁸⁵ links, and the members 14 constitute flexible connectors for adjacent links; otherwise the construction of the bracelet section is substantially identical to that of Figs. 1 and 2. ⁹⁰

The further variation illustrated in Figs. ⁹⁰ 4 and 5 comprises interconnected links each including a body portion 28 of leather, fabric or the like, an eyelet member 20 reinforcing its central opening, and an outer reinforcement or rim 21 embracing the periphery of the body portion; and in this instance the connecting members are formed with a single crossbar 24.

Other variations in the structural details of the improved strap or band are obviously ¹⁰⁰

within the purview of this invention, and it will be apparent that the improved article may be employed as a section of a watch bracelet equipped with any suitable form of connectors, clasps or extensible attachments, or may be of sufficient length to constitute a permanently closed or separable band, bracelet or belt. In the form of Fig. 1, the leather strap section 8 may be attached to the lugs 25 of a wrist watch 26 by means of a pin 27 extending through an eye at the end of the strap and into apertures in the lugs 25. From the foregoing it is evident that the body of the bracelet strap or band may be formed in a continuous strip or in separate sections, of material such as leather, fabric or the like which, when cut out to provide the desirable openings, may be relatively weak or flexible and subject to distortion or damage under strain; that the metal eyelets which are fitted to said openings reinforce and tend to stiffen the body material; and that any longitudinal strain upon the bracelet section is borne by the relatively rigid eyelets and the connecting members which straddle the openings and engage the eyelets. Such a construction not only represents a mechanical improvement but more especially lends itself to attractive and ornamental display, for the respective parts of the bracelet may exhibit contrasting textures, colors, configurations or designs which enhance the value of the article and satisfy the vogue of the movement in useful and decorative jewelry.

I claim:

1. A bracelet band or the like comprising a body having spaced apertures therethrough, reinforcing members fitted to said apertures, and connecting links straddling adjacent apertures and engaging their reinforcements so that longitudinal strain upon the band is borne by said reinforcing members and links.
- 45 2. A bracelet band or the like comprising a continuous body having spaced apertures therethrough, reinforcing eyelets fitted to said apertures, and metal links encircling adjacent portions of adjoining eyelets, the eyelets and links bearing longitudinal strain upon the band.
- 50 3. A bracelet band or the like comprising a body having apertured portions spaced longitudinally from each other, reinforcing eyelets fitted to the apertures of the respective portions, and metal links encircling adjacent sides of adjoining eyelets for flexibly interconnecting said portions.
- 55 4. A bracelet band or the like comprising a body having apertured portions spaced longitudinally from each other, reinforcing eyelets fitted to the apertures of the respective portions, metal rims embracing the peripheries of said portions, and metal links encircling adjacent sides of adjoining eye-

lets for flexibly interconnecting said portions.

Signed by me at Providence, Rhode Island, this fourth day of December, 1930.
